UNITED STATES PATENT OFFICE.

ERNEST V. JOHNSON, OF CHICAGO, ILLINOIS.

FIREPROOF FLOOR CONSTRUCTION.

1,076,040.

Specification of Letters Patent.

Patented Oct. 21, 1913.

Application filed December 9, 1910. Serial No. 596,418.

To all whom it may concern:

Be it known that I, ERNEST V. JOHNSON, a citizen of the United States, residing in Chicago, in the county of Cook and State of Illinois, have invented a new and useful Improvement in Fireproof Floor Construction, of which the following is a specification.

My invention relates to improvements in fireproof floor construction for buildings, and more particularly to hollow tile fireproof floor constructions.

The object of my invention is to provide a hollow tile fireproof floor which will be of a simple, efficient, light, strong and durable construction, and which may be rapidly and cheaply erected and in which all the tile will be rigidly and firmly united and bonded together by and individually surrounded 20 and incased in a continuous network of cement or concrete.

My invention consists in the means I employ to practically accomplish this object or result as herein shown and described and 25 more particularly specified in the claims.

In my invention, each of the hollow tiles is provided at each of its open upright faces with a wire-mesh closure of light wire netting secured thereto by metal brads or 30 wooden pegs driven into the tile at each end thereof. The mesh of the wire netting or screen is sufficiently fine or close, preferably about twelve to the inch, to prevent liquid Portland cement, concrete or grouting passing through the wire mesh. The hollow tiles with their hollows thus closed at each end by the wire mesh or netting are then laid or set in place on the customary portable centering or false floor work and between 35 the horizontal steel beams or girders of the building framework, a space preferably of about three quarters of an inch being left between the upright end faces of the adjacent tiles and between the adjacent rows 40 of tiles, which are laid in the usual way to break joints. The continuous open space network between the side and the end faces of the tile is then filled in with liquid Portland cement, concrete or grouting, the same 45 being poured in in a liquid condition so that it will solidly or completely fill all the spaces between the upright side and end faces of adjacent tiles, and thus form, when the cement sets, a solid and continuous network 50 of cement or concrete upright webs by which each and every tile is surrounded and em-

braced on all its upright faces, and in which the tiles are embedded and by which all the tile are bonded and united together in one monolithic cement concrete mass or network. The wire mesh closures at both ends of each hollow tile are most conveniently secured to the end faces of the tile by small metal brads or tacks, which may be readily driven into the tile if the same are soft. 60 Where hard burned tile are employed, the wire mesh closures are preferably secured in place on the end faces of the tile by wood pegs driven into the holes which are customarily formed at the corners of the tile 65 to insure perfection of hollow tile at the corners.

In the accompanying drawing, Figure 1 is a perspective view, partly in vertical section, and partly broken away, of a hollow tile fireproof floor construction embodying my invention. Fig. 2 is a perspective view of one of the hollow tile. Fig. 3 is an enlarged, detail, partial section on line 3—3 of Fig. 2.

In the drawing, 1, 2 represent longitudinally and transversely extending steel beams or girders of the building framework and 3 a portion of the portable centering or false floor used in the construction or erection of 85 the hollow tile fireproof floor. Each of the hollow tile 4 has a plurality of hollows 5 extending through it from end to end. As indicated in the drawing, each of the hollow tile is furnished with six of these hollows 5, their number being varied according to the size of the tile, the tile being usually made about twelve inches long and twelve inches wide, and their height or vertical dimension being varied according to the thickness and strength of the floor to be constructed therewith. Each of the tile 4 is provided at each of its open ends with a wire mesh closure 6 secured thereto by brads or pins 7 driven into the tile. If the tile 90 are soft, the brads or pins 7 may be metal and driven directly into the tile. If, however, the tile are hard, the brads or pins 7 are preferably of wood and made of larger size and driven into the holes 8 which ordinarily extend through the tile from end to end at the corners thereof. The wire mesh closure 6 preferably laps over or covers about one half the thickness of the exterior webs 9 of the tile, so that the portion of the end face 10 of the tile will be left free and exposed for more direct contact with the 100

liquid cement or concrete which is poured into the continuous network space 11 between the adjacent side faces 12 and end faces 10 of contiguous tile.

5 In constructing the floor, the tile are first laid or placed in position between the horizontal steel beams or girders 1, 2 of the frame and upon the portable centering or false flooring 3, with an open space 11, preferably about three-quarters of an inch in width between the side and end faces of adjacent tile. Liquid Portland cement, concrete or grouting is then poured into the open spaces 11 between the side and end faces of the tile, the wire mesh closure 6, 6 at the open ends of adjacent tile preventing the liquid material from entering the hollows 5 of the tile. Each of the tile 4 is thus embedded in and surrounded at all of its upper side and end faces by the cement, concrete or grouting 14 which forms, when set, a solid, continuous network of cement, concrete upright webs which bond and unite all the tile together. The tile 4 are laid 20 with their open ends adjacent and in rows or courses 15 extending between the steel beams or girders 1, 1, the tile in one row

breaking joints with those in the adjacent row.

I claim:—

1. A hollow tile having an opening therein and provided with a wire mesh closure at one end thereof and adapted to prevent liquid cement from flowing into the interior of the tile, and means for permanently securing said wire mesh closure to the tile, said means including a wedge shaped brad passing through the wire mesh closure and extending into said opening in the tile, whereby the tile with its wire mesh closure may be 35 shipped without danger of the closure becoming displaced, substantially as specified.

2. A hollow tile having holes 8 and provided with flat wire mesh closures at the open ends thereof to prevent liquid cement 40 from flowing into the interior of the tile at either end, said closures being secured to the tile by brads extending through the closures and seated in the holes 8 of the tile, substantially as specified.

ERNEST V. JOHNSON.
